Thomas O. Rorke's
Improvement in Siphon-Steam-Pump.

117450

PATENTED JUL 25 1871

UNITED STATES PATENT OFFICE.

THOMAS O'RORKE, OF PITTSBURG, PENNSYLVANIA.

IMPROVEMENT IN SIPHON STEAM-PUMPS.

Specification forming part of Letters Patent No. 117,450, dated July 25, 1871.

To all whom it may concern:

Be it known that I, THOMAS O'RORKE, of Pittsburgh, in the county of Allegheny and State of Pennsylvania, have invented a new and useful Improvement in Siphon Steam-Pump; and I do hereby declare that the following is a full, clear, and exact description thereof, reference being had to the accompanying drawing and to the letters of reference marked thereon.

The nature of my invention consists in a siphon steam-pump having a detachable and adjustable tube arranged in it around the steam-pipe and concentric to it, and extending forward and backward of the outlet of steam.

To enable others skilled in the art to make and use my invention, I will proceed to describe more fully its construction and operation.

In the accompanying drawing which forms part of my specification, Figure 1 is a vertical and longitudinal section of my improvement in siphon steam-pump. Fig. 2 is a transverse section of the same at line *y* of Fig. 1.

A represents the casing or shell of the pump, in the chamber *B* of which is a steam-pipe, *C*. The shell *A* is provided with three openings, *D*, *e*, *f*, which are furnished with screw-threads for the purpose of attaching the several pipes, viz., the steam-pipe at *D*, the water-supply pipe at *e*, and the pipe used for conveying water from the pump at *f*. The shell *A* and pipe *C* are cast in one piece, the pipe *C* being formed in the core which forms the chamber *B* of the shell *A*, which process of casting is well understood by the skillful molder. Around the steam-pipe *C*, concentric to it and the outlet of the chamber *B*, is arranged a tube, *h*, which extends forward and aft of the outlet of the steam-pipe *C*, as shown in Fig. 1.

The operation of my improvement is as follows: Steam flowing into the pipe *C* and out

into chamber *B* will cause the water to flow into chamber *B* through the pipe attached at *e*, and the forward flow of steam from the pipe *C* will cause the water to flow out from chamber *B* through the opening *f*, dividing the outflowing current into two parts, one part of it flowing through the tube *h* and the other part through the space *x* between the shell and tube. By arranging the tube around the steam-pipe in the manner hereinbefore described the pump will act more efficiently and with a less pressure of steam than it will without the tube *h*, and the flow of water from the pump will be steady and regular, which is not the case with the ordinary steam-pump known as siphon steam-pump. By having the tube *h* adjustable the pump can be adapted to fluids of different specific gravity and for lifting them at different elevations, which is a great consideration in a siphon steam-pump.

It will be observed that when the tube *h* is removed from the shell *A* the pump will be of the ordinary construction; therefore, I desire it to be clearly understood that the main feature of my invention consists in the use of the tube *h* with relation to the steam-pipe *C* and the outlet of the chamber *B*.

Having thus described the nature, construction, and operation of my improvement, what I claim as of my invention is—

A siphon steam-pump having a detachable and adjustable tube around the steam-pipe *C* extending forward and aft of its outlet, and arranged concentric to it and the outlet of the chamber *B*, substantially as herein described and for the purpose set forth.

THOMAS O'RORKE.
